EDUARDO ROJO Y REYES, OF HABANA, CUBA, ASSIGNEE TO HAVANA COMMERCIAL CO.,
OF NEW YORK, N. Y., A CORPORATION OF NEW JERSEY.

CIGARETTE AND CIGAR WRAPPING MACHINE.

Application filed June 8, 1925, Serial No. 35,594, and in Cuba January 24, 1925.

This invention is an improvement in wrapping machines, and more particularly in machines for compacting a selected number of articles, such as cigars or cigarettes, 5 into a formation substantially rectangular in cross section, irrespective of the cross sectional shape of the article.

In a certain type of wrapping machine for articles like cigarettes and cigars, the articles are assembled in blocks of a selected 10 number, and wrapped in a wrapper, the folding of which about the block of assembled articles is controlled to operate by the movement of the assemblage past the 15 folding mechanism.

The articles are usually massed or bunched by discharging a selected number from a magazine, either the full complement 20 of articles, or an aliquot part thereof. In the latter case a distinct operation of ejection is required for each aliquot part.

With articles which are cylindrical or circular in cross section and of uniform dimensions, it is not difficult to eject from a magazine 25 a selected number. When however the articles vary in size, and especially when they are not circular in cross section, the ejection is not so easily carried out.

At the present time, cigars and especially 30 cigarettes differ greatly in cross sectional shape, and with oval cigarettes and cigars, methods of ejecting a selected number from the magazine are not satisfactory, and when ejected the articles do not lie compactly.

One of the primary objects of the present invention, is the provision of mechanism 35 for simultaneously ejecting from a magazine the aliquot parts of a selected number of articles, such as cigars or cigarettes, and for afterwards bunching the parts in a compact 40 block, wherein the parts are superposed one upon the other.

Another object of the invention is the provision of means for similarly arranging a 45 set of articles of similar shape and size but oval in cross section.

To the accomplishment of the foregoing and such other objects as may hereinafter appear, the invention consists in the construction and novel combination of parts 50 fully described hereinafter, illustrated in the accompanying drawings, and pointed out in the claims appended hereto, it being understood that various changes in the

form, proportion, size and minor details of 55 construction within the scope of the claims, may be resorted to without departing from the spirit of the invention.

In the drawings forming a part hereto, Fig. 1 is a front view of the magazine, at 60 substantially the line 1—1 of Fig. 3.

Figs. 2, 4 and 6 are sections on the lines 2—2, 4—4 and 6—6 respectively, of Fig. 3.

Fig. 3 is a plan view.

Fig. 5 is a perspective view of one of the 65 discharge chutes for the magazine.

Fig. 7 is a view similar to Fig. 6 showing the parts in another position.

The present embodiment of the invention, which is adapted for use in connection with 70 the machine forming the subject matter of my co-pending application Ser. No. 35,593 of even date herewith, comprises a magazine with a bottom composed of three channels, 1, 2, and 3, the bottoms of the channels 75 being in stepped relation as shown, with the bottom of the channel 3 at the highest level. The channels 1 and 3 are adapted to receive articles from the body 4 of the magazine, and in the bottom of each channel means is 80 provided for segregating a plurality of articles, and for holding them in spaced parallel relation.

Each of the said means is constituted by 85 a number of partitions 5, which form between them and the walls of the channel, a number of troughs, each for receiving a single article. Where it is desired to pack the articles in superposed rows of aliquot parts of a selected number, as for instance 90 10 cigars in two rows of five each, there are five troughs in each channel, but the number of troughs will depend upon the number of articles it is desired to pack in each row.

Deflecting plates 6 of angular formation 95 are arranged at the outer sides of the channels, for deflecting the articles placed in the magazine into the channels. An arc-shaped deflector 7 is arranged between the channels, above the channel 2, and these 100 deflectors are supported by a frame 8 which is mounted for transverse sliding movement between the body of the magazine and the channels.

It will be noticed referring to Fig. 2 that 105 each of the deflectors 6 has a portion extending through a slot 9 in a magazine wall, and a lever 10 is provided for vibrating or

reciprocating the frame, the lever being connected to the frame by a link 11. The deflectors 6 are perforated as shown, and the frame is a species of grid, being composed of side members slideable in guides in the front and rear walls of the magazine, and connected by cross bars 12 at the inner ends of the deflectors 6, and at the ends of the deflectors 7, and by spaced pins 13 between the deflectors.

The pins 13 are spaced apart at equal distances, and at distances somewhat greater than the spacing of the partitions 5. The arrangement is such, that the articles in the magazine will be fed down between the pins 13, into the channels, with their long axes parallel with the pins and the partitions, and the articles will fall into the troughs between the partitions. These troughs are of a size to hold a single article, and any desired form of pusher is provided for ejecting each series of articles from the channel.

The pusher for each channel may be a series of fingers, corresponding in number to the number of troughs, and moving through an opening 14 in the rear wall of the magazine. Referring to Fig. 4 it will be seen that a door 15 is provided in the side wall, the door being hinged at 16 at its top, and at its lower edge the door carries a number of fingers 17, which at their lower ends are in rear of the partitions 5. The fingers prevent the escape of articles at the rear of the magazine.

In front of the magazine and spaced apart therefrom, mechanism is provided for compacting the articles of each row, and for moving the rows laterally toward each other, into position one above the other. The said means includes a casing 18 which is supported on the table 19 which supports the magazine, and this table may be the frame carrying the wrapping mechanism shown and described in the application above mentioned. The casing has its long axis transverse to the path of movement of the articles issuing from the magazine, and it is provided with two passages or channels 20 and 21 extending entirely through the casing from front to rear, and from one end thereof to near the other. One channel 20 extends from the left end of the casing, and the other from the right end, and they lap at their inner ends as shown, in Figs. 6 and 7.

A slide is arranged in each of the channels, the slides 22 and 23 being movable toward and from the inner end of the respective channel, and cooperating with the said inner end thereof, to compact the articles delivered into the channel. Each of the slides has connected thereto a pin 24 and 25 respectively, and the pins move in slots 26 in the casing. Levers 27 are connected with the pins by means of links 28, and it will

be evident that when the levers are vibrated, the slides will be moved longitudinally of the channels.

The bottom of each channel 20 and 21 is formed by a plate 29 and 30 respectively, and these plates are connected with the slides, the plate 29 to the slide 22, and the plate 30 to the slide 23. The plates move on the bottoms of the channels, and when articles are delivered into the channels in a manner to be presently described, they are delivered onto the plates.

When the cigars or cigarettes are cylindrical, they may be delivered into the channels 20—21 in any angular order. That is the angular position of the several articles is immaterial. When however the cigars or cigarettes are oval in cross section, it is desirable in the formation of a symmetrical package that the long axes of the oval cross section be parallel and inclined to the vertical. In order to insure that they will be so arranged in the channels 20—21, mechanism is interposed between the troughs of the magazine, and the channels, that is between the magazine and the casing 18.

The said mechanism is for each set of segregating troughs, a set of tubular guides which for convenience are assembled in an integral structure comprising a base 31 and a nozzle portion 32 extending laterally from the base, and provided with bores 33 corresponding in number to the number of troughs. The base is secured to the front wall of the casing, at the front ends of the troughs, and with the bores 33 of the nozzle in register with the troughs. Each of these bores as shown in Fig. 5 is circular in cross section at its entrance end, and oval in cross section at its discharge end, and each bore tapers from the entrance to the discharge. The walls of the bores are of a nature to offer no resistance to the passage of the articles, but the articles receive an angular movement in their passage through the bores, in the same direction, so that they emerge with their axes parallel and inclined. The pushers 34 which move in the channels, pass on opposite sides of the plate 29, the upper pusher moving the upper row of articles into the channel 20, while the lower pusher moves the lower row into the channel 21.

At this time the slides 22 and 23 are at the outward limit of their stroke, and the articles of each set are moved into the appropriate channel between the front end of the slide and the closed end of the channel. When the machine is handling articles oval in cross section, the front ends of the slides, and the closed ends of the channels should be beveled as shown in Figs. 6 and 7, on lines parallel with the long axes of the ovals.

When the articles have been placed in the casing as above mentioned, the slides are

moved toward the inner walls of the channels, and each set of articles is compacted between the inclined walls of the slide and channel ends. The articles are not pressed 5 tightly, but merely massed, and held in the desired relation.

At this moment the pushers 34 move forwardly, ejecting the compacted cigarettes from the channels 20-21, into the wrapping channel of the machine forming the subject matter of the above mentioned application. The slides are then withdrawn, another charge of articles is inserted in front of each slide, and the operation is 15 repeated.

The pushing fingers which move the articles out of the troughs need only be of a length to push the articles from the troughs. The next movement of the fingers 20 to eject another charge of articles, will eject the first charge from the mechanisms 30-32.

In operation, the articles are fed into the magazine, and by means of the reciprocating grid they are dropped into the troughs of the channels with their axes parallel, and in segregated relation. By means of the pushers not shown, the articles in each set are shoved out through the structure 31-32, into the channel 20 or 21 as 25 the case may be. When the slides move toward each other, each set of articles is compacted, and by the pushers 34, the compacted sets are moved out to the wrapping channel, or they might be moved directly 30 into a suitable container, as for instance a box if desired.

I claim:

1. A machine for assembling articles of a similar shape and size, such as cigars and cigarettes, into masses of superposed layers, including a plurality of sets of open troughs, each of a size to receive a single article, means for supplying articles to the troughs, means to simultaneously eject all of the articles from the troughs, means for receiving the ejected articles of each set, for compacting the articles, and for moving the sets laterally, with one set above the other, and means through which the articles are ejected 40 from the trough for imparting angular movement to the articles as they move therethrough.

2. A machine for assembling articles of a similar shape and size, such as cigars and cigarettes, into masses of superposed layers, including a plurality of sets of open troughs, each of a size to receive a single 45

article, means for supplying articles to the troughs, means to simultaneously eject all of the articles from the troughs, means for receiving the ejected articles of each set, for compacting the articles, and for moving the sets laterally, with one set above the other, and means to similarly arrange articles of oval cross section as they pass from 50 the troughs to the compacting mechanism. 60

3. A machine for assembling sets of articles of similar shape and size into superposed layers, including a plurality of sets of open troughs, each of a size to receive 55 a single article, means to eject the articles from the troughs, mechanism to which the sets of articles are delivered for compacting the sets, and for moving them laterally into position one above the other, and means 65 interposed between the troughs and the compacting mechanism, through which the articles are pushed, for imparting angular movement to the articles in the same direction. 70

4. In a machine for assembling articles of a similar shape and size, a magazine having the bottom thereof provided with a plurality of channels extending alongside each other, partitions extending longitudinally 75 of the side channels, and dividing them into troughs, each for receiving an article to be assembled, means to arrange the articles in substantially parallel relation, and feed them into the troughs, said means including a grid moving transversely of the channels, and having openings substantially parallel with the axes of the channels of 80 a size to permit passage of a single article. 85

5. In a machine for assembling articles of a similar shape and size, a magazine having the bottom thereof provided with a plurality of channels extending alongside each other, partitions extending longitudinally 90 of the side channels, and dividing them into troughs, each for receiving an article to be assembled, means to arrange the articles in substantially parallel relation, and feed them into the troughs, said means including a grid moving transversely of the channels, having openings substantially parallel with the axes of the channel of a size 95 to permit passage of single article, said grid having deflectors for guiding the articles into the openings. 100

Signed at Habana in the Province of Habana and Republic of Cuba this 27th day of May A. D. 1925.

EDUARDO ROJO y REYES.
